UNITED STATES PATENT OFFICE

JOHN P. BROCKWAY, OF CORONADO, CALIFORNIA

PROCESS OF REPRODUCING IMAGES ON RUBBER SURFACES

No Drawing.

Application filed February 28, 1929. Serial No. 343,575.

My invention relates to a process of reproducing images on rubber surfaces, more particularly on surfaces composed of hard rubber, and the objects of my invention are: first, to provide a new and novel process of reproducing images; second, to provide a novel process of reproducing images by photographic process; third, to provide a new and novel process of reproducing images on rubber surfaces; fourth, to provide a process of reproducing images which provides images that are very clear and durable, and fifth, to provide a process of this class which is very simple and economical of operation and efficient in its action.

With these and other objects in view as will appear hereinafter, my invention consists of the certain novel process as will be herein-after described in detail and particularly set forth in the appended claims.

My process consists in first taking hard surfaced rubber and providing it with a highly polished finish; then washing the hard surface in hydrochloric acid; then wiping the surface dry; then photographing an impression of an image from a transparent object or member, such as a film or negative placed in front of the hard rubber finished surface, by exposure to the light; then developing the same on the surface by placing the hard rubber surface in a bath of nitric acid and water of approximately fifty per cent. nitric acid and fifty per cent. water. This nitric acid and water will etch out the light affected portion leaving a clear image of the object on the transparent member on the hard rubber surface.

I have found by experimentation that the washing of the hard surface in hydrochloric acid may be omitted, but the results obtained are possibly not so satisfactory in some cases.

Though I have described a particular process of reproducing images on rubber surfaces, I do not wish to be limited to this particular process, but desire to include in the scope of my invention the process substantially as set forth in the appended claims.

Having thus described my invention, what I claim as new and desire to secure by Letters Patent is:

1. The herein described process of reproducing images on rubber surfaces, comprising providing the rubber surface with a highly polished surface, then subjecting the surface to a bath of hydrochloric acid, then, wiping said surface dry, then placing an image on a transparent member in front of said rubber surface, then exposing the same to light, and then developing the rubber surface by placing the same in a bath of nitric acid, fifty percent, and water, fifty percent. 55

2. The herein described process of reproducing images on hard rubber finished surfaces, comprising the subjecting of the surface to a bath of hydrochloric acid, then wiping said surface dry, then placing a transparent member with an image thereon in front of said rubber surface, then exposing the same to light, then developing the surface by placing the same in a bath of nitric acid, fifty 60 percent, and water, fifty percent. 65

3. The herein described process of reproducing images on finished hard rubber surfaces, comprising the subjecting of the surface to a bath of hydrochloric acid, then drying said surface, then placing a film with an image thereon in front of said rubber surface and exposing the same to light, then developing the rubber surface by placing the same in a bath of nitric acid and water. 75

4. The herein described process of reproducing photographic images on hard rubber finished surfaces, comprising polishing said hard rubber surface, then subjecting said polished surface to a bath of hydrochloric acid, then drying said surface, then placing a film with an image thereon in front of said rubber surface and exposing the same to light, then developing the rubber surface by placing the same in a bath of nitric acid and water. 80

5. The herein described process of reproducing photographic images on hard rubber finished surfaces, comprising polishing said hard rubber surface, then subjecting said polished surface to a bath of hydrochloric acid, then drying said surface, then placing a film with an image thereon in front of said rubber surface and exposing the same to light, then developing the rubber surface by 85 100

placing the same in a bath of nitric acid, fifty percent, and water, fifty percent.

6. The herein described process of reproducing images on rubber surfaces, comprising providing the rubber surface with a highly polished surface, then placing a film with an image thereon in front of said rubber surface and exposing the same to light, then developing the rubber surface by placing the same in a bath of nitric acid and water.

10 7. The herein described process of reproducing images on rubber surfaces, comprising providing the rubber surface with a highly polished surface, then placing a film with an image thereon in front of said rubber surface and exposing the same to light, then developing the rubber surface by placing the same in a bath of nitric acid, fifty percent, and water, fifty percent.

20 In testimony whereof, I have hereunto set my hand at San Diego this 21st day of February, 1929,

JOHN P. BROCKWAY.
